UNITED STATES PATENT OFFICE.

FINDLAY JACK, OF PAWTUCKET, RHODE ISLAND, ASSIGNOR TO BROWN & SHARPE MFG. COMPANY, OF PROVIDENCE, RHODE ISLAND.

MILLING-MACHINE ATTACHMENT.

Application filed June 18, 1926. Serial No. 116,832.

This invention relates to certain new and useful improvements in milling machine attachments and pertains more particularly to a device which is attachable to the movable table for the purpose of quickly returning the table to its initial or starting point after the work on the table has passed beneath the cutting tool.

The primary object of the invention is to provide a device of this type which is attachable to either end of the table to thereby enable the device to be applied in accordance with the space permitted, since owing to the close quarters assigned to small milling machines, it is necessary that the device of this character be applied according to the available space.

A further object of the invention is to provide a device of this character which is of simple and compact construction, positive and quick in its movement, and composed of a minimum of parts.

In the drawings:—

Fig. 1 is an end elevation of the invention applied to a milling machine, the latter shown in fragment;

Fig. 2 is a top plan view, and

Fig. 3 is a section on line 3—3 of Fig. 2.

In proceeding in accordance with the present invention, the attachment is formed of a substantially U-shaped frame 1, the arms 2 of which are formed at their outer or free ends with circular heads 3 and 4. Hooks or fingers 5 project upwardly from the frame 1 and hook over either end of the movable bed or carriage C of the milling machine. A central boss 6 is carried by the frame 1 and is located between the hooks 5, and receives therein a bolt 7 having a nut 8 thereon, the lower end of the bolt being turned at an angle to form a finger that engages the under face of the bed C. From the foregoing it will be seen that the frame can be clamped onto either end of the table both easily and quickly.

The shaft 10 extends through the heads 3 and 4 and through collars 11 and 12. The collar 11 is rigidly secured to a drum or spool 13 by means of a screw 14, the shaft however passing loosely through the collar 11. The collar 12 is keyed at 15 to the shaft and is hereby held on a reduced part 16 of the shaft and against shoulder 17 resultant from the reduced part. A journal ring 18 is secured by means of a screw 19 to the

sleeve or drum 13. A coil tensioning spring 20 which is partly broken away at its center in Fig. 3, is employed to tension the drum 13, and has one end 21, secured in collar 11, while its opposite end 22 is secured in the collar 12. The head 3, which is rigidly carried by the frame 1, is formed with a circular series of openings 24, to selectively receive the free end of a locking pin 27, which latter projects through an opening provided therefor in an adjusting disk 25, which latter is keyed at 28 to the shaft 10, and is held on the latter by a nut 26. The disk 25, is provided with peripheral opening 29, to receive a pin or the like whereby to enable the disk 25, to be turned so as to adjust the tension of the spring 20.

A chain 30 is secured to the drum at one end and at its opposite end is suitably secured to the stationary bed B of the milling machine, for example by means of a screw 31; a bolt or screw similar to the screw 31 is employed to secure the chain to the drum.

The invention is employed in connection with a milling machine of the type shown in the patent to Stedman, No. 893,205 dated July 14, 1908. The movable bed or carriage C is operated by power on its working stroke and upon completion of the latter, the power is disengaged from the bed C. During working stroke of the bed C, power is stored up in the drum 13, and upon release of the bed from the driving power of the machine, the drum, under the influence of the wound up spring will wind the chain thereabout thereby to move the carriage to initial position ready to be again given its working stroke by the driving power of the machine.

Having thus described my invention what I claim as new and desire to secure by Letters Patent is—

1. An attachment for milling machines of the type wherein the carriage is operated by driving means on its working stroke and upon completion of such stroke the driving means is disengaged from the carriage including a frame, means to secure the frame to the carriage, a spring tensioned drum on the frame, means to regulate the tension of the spring, and a chain connected to the drum and to the bed of the machine to tension the spring upon working stroke of the carriage and upon disengagement of the

driving means from the carriage to automatically restore the carriage to initial position.

2. An attachment for milling machines of the type wherein the carriage is operated by driving means on its working stroke and upon completion of such stroke the driving means is disengaged from the carriage including a power device, means connected to 10 the device and to the bed of the machine for actuating the device to store-up power therein on the working stroke of the carriage and upon disengagement of the driving means from the carriage to automatically restore 15 the carriage to initial position.

3. An attachment for milling machines of the type wherein the carriage is operated by driving means on its working stroke and upon completion of such stroke the driving means is disengaged from the carriage including a rotatable power device, means to tension the device, means to attach the device to the carriage of a milling machine, and flexible means connected to the device 20 and to the bed of the machine whereby upon movement of the carriage on its working stroke the flexible means will actuate the device to store-up power therein, and upon disengagement of the driving means from the 25 carriage will wind the flexible means on the device to thereby automatically move the carriage to initial position.

30

4. An attachment for milling machines of the type wherein the carriage is operated by driving means on its working stroke and 35 upon completion of such stroke the driving means is disengaged from the carriage including power means, means to attach said means to either end of a milling machine carriage, and means whereby upon the working stroke of the carriage power will be stored up in the power means and upon disengagement of the driving means from the carriage will automatically restore the carriage to initial position. 40

5. An attachment for milling machines of the type wherein the carriage slides on a bed and is operated by driving means on its working stroke and upon completion of such 45 stroke the driving means is disengaged from the carriage including actuating means, means to attach said actuating means to one of the first two named elements of the machine, and means connected to the actuating means and to the other of said two first 50 named elements whereby to energize the actuating means upon the working stroke of the carriage, and upon disengagement of the driving means from the carriage to automatically restore the carriage to initial position. 55

In testimony whereof I have signed my name to this specification.

FINDLAY JACK.
